UNITED STATES PATENT OFFICE.

DAVID W. STOCKSTILL AND THOMAS J. McGEARY, OF WASHINGTON, D. C.,
ASSIGNORS OF ONE-THIRD TO E. W. ANDERSON, OF SAME PLACE.

PLASTERING AND ORNAMENTING WALLS AND CEILINGS.

SPECIFICATION forming part of Letters Patent No. 245,237, dated August 2, 1881.

Application filed May 28, 1881. (No model.)

To all whom it may concern:

Be it known that we, DAVID W. STOCKSTILL and THOMAS J. McGEARY, both of Washington, in the county of Washington and District 5 of Columbia, have invented a new and valuable Improvement in Plastering and Ornamenting Walls and Ceilings; and we do hereby declare that the following is a full, clear, and exact description of the construction and operation of 10 the same, reference being had to the annexed drawings, making a part of this specification, and to the letters and figures of reference marked thereon.

Figure 1 is a plan view of a mold forming a 15 center-piece. Fig. 2 is a sectional view of the same. Figs. 3, 4, 5, and 8 are cornice-molds; and Figs. 6 and 7 are sections of the same.

This invention has relation to improvements 20 in the art of plastering, whereby centers, cornices, and ornaments of any character can be produced by the direct application of the newly-mixed or soft plaster or composition to the wall under a molding pressure.

Heretofore it has been customary for plasterers to purchase previously-molded centers, 25 cornices, and ornamented work used in decorating the interiors of apartments and buildings; and right-line cornices and moldings have been formed on the wall with newly-mixed 30 plaster by means of a former or profile scraper, which is drawn along the outer portion of the mass of plaster. A mold has been secured beneath a ceiling, and liquid composition run in from above the ceiling, and the liquid composition then permitted to dry and adhere to 35 the ceiling before the withdrawal or removal of the mold. This method of forming ornamented walls or ceilings, however, differs from the method or process herein described and 40 claimed.

The present invention has no relation to such devices, but is designed to enable the plasterer, with the same newly-mixed stock which he uses in surface-finishing the wall, to put up 45 centers, cornices, or ornamental devices of any figure or pattern which will readily draw from a mold. The process is so simple that, if desired, an entire wall can be ornamented in low 50 relief or intaglio by any plasterer of ordinary skill in his trade.

The invention consists, first, in the art or process of forming centers, cornices, or other ornamental surfaces in place by molding the plaster immediately on the wall; and, secondly, in providing a mold adapted to receive 55 the plaster, to apply the same to the wall, and to draw easily therefrom, substantially as hereinabove set forth.

In the accompanying drawings we have designed to illustrate several forms of molds 60 which may be used in carrying out this invention. These forms may be varied in many ways, the object being to provide a mold which is light enough to be readily handled, and which has sufficient stiffness or body to support the 65 material placed upon it and to withstand the pressure used in applying the same to the wall. In practice it is preferred to form these molds by pressure from sheet-zinc, or some composition in which zinc is an element, although a 70 different material may be used, if thought desirable.

The molds are pressed by means of dies, usually, and may have the configuration in relief or intaglio and according to any design. The letter A indicates a mold for a central ornament, and B a mold for a cornice. These molds should be provided with flanges a, which are designed to serve as a guide to the workman, enabling him to apply the plaster with precision 80 and facility. Handles b may also be attached, and will render the molds much more convenient. A miter-mold can be made by forming at one end of the main mold a projecting flange of the same pattern as indicated in the drawings at c.

For continuous work, such as cornices, moldings, and friezes, the molds employed are made sufficiently long to be conveniently raised and handled by the plasterer, about thirty inches 90 being the usual length. These molds are usually provided with shouldered or abutting flanges d, so that a neat joint in the plastering may be effected and the continuity of the ornamentation preserved. In the manufacture 95 of these molds it is important to have the indentations rounded or obtuse, and the walls sufficiently beveled or inclined to enable the mold to draw easily from the plaster after the latter has set. The top of the mold is open to 100

receive the plaster, which is put therein, in its newly-mixed state, in sufficient quantity to project a little, so that when the mold is pressed in place against the wall the plaster will adhere thereto. After the plaster has set the mold can be withdrawn for use again. In preparing the mold it is advisable to oil or wet its interior surface before putting in the plaster, the drawing of the mold being facilitated thereby. As the metal which is usually employed for these molds is not rigid, but possesses a certain amount of elasticity, it can readily be sprung away from the work.

This invention is designed to enable those who build houses to greatly enrich the interior and exterior of the same at small expense. It will assist the plasterer in his journey-work, rendering it of more value, and will save the cost of transporting plaster-castings from place to place. Houses in country localities can be ornamented as cheaply as those in cities and towns. A saving of material is also designed to be accomplished by this invention, because in practice the plasterer will only use sufficient stock to form the ornamental surface and the attachment edge therefor.

Having described this invention, what we claim, and desire to secure by Letters Patent, is—

1. The process of pressure-molding plaster or composition described, consisting in first filling a portable mold with soft plaster or composition of proper consistency to hold its form so that it shall project a little from the mold; second, moving the filled mold against the wall or surface, so that the plaster or composition shall adhere by its projected portion; and, finally, removing the mold, leaving the ornamentation in place, substantially as specified.

2. A pressed sheet-metal mold provided with guide-flanges, and adapted to receive the plaster or composition, to apply the same to the wall, and to draw easily therefrom, substantially as specified.

3. A plasterer's mold for ornamental work, pressed in form from sheet-zinc or zinc composition, substantially as specified.

In testimony that we claim the above we have hereunto subscribed our names in the presence of two witnesses.

DAVID W. STOCKSTILL.
THOS. J. McGEARY.
